US00D804461S

(12) **United States Design Patent** (10) **Patent No.:** **US D804,461 S**
(45) **Date of Patent:** **** Dec. 5, 2017**

(54) **MOBILE TERMINAL**

- (71) Applicant: **SAMSUNG ELECTRONICS CO., LTD.**, Suwon-si, Gyeonggi-do (KR)
- (72) Inventors: **Ji-Sang Park**, Yongin-si (KR); **Seung-Ho Lee**, Guri-si (KR); **Jin-Hoo Lee**, Seoul (KR); **Jae-Woong Chung**, Seongnam-si (KR); **Du-Yeong Choi**, Anyang-si (KR)

- (73) Assignee: **SAMSUNG ELECTRONICS CO., LTD.**, Gyeonggi-Do (KR)

- (**) Term: **15 Years**

- (21) Appl. No.: **29/605,735**

- (22) Filed: **May 30, 2017**

Related U.S. Application Data

- (63) Continuation of application No. 29/546,792, filed on Nov. 25, 2015, now Pat. No. Des. 791,099.

(30) **Foreign Application Priority Data**

Jun. 19, 2015 (KR) 30-2015-0030973

(57) **CLAIM**

The ornamental design for a mobile terminal, as shown and described.

DESCRIPTION

FIG. 1 is a front perspective view of a mobile terminal, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a rear perspective view thereof.

The broken lines, shown in the figures, which are immediately adjacent to the solid lines represent the bounds of the claim. All other broken lines, including features within broken line boundaries, and broken lines outside the claimed design, are directed to environment. The broken lines form no part of the claimed design.

1 Claim, 6 Drawing Sheets
